(57) **CLAIM**

The ornamental design for a knee brace as shown and described.

DESCRIPTION

FIG. 1 is top, front, left perspective view of a knee brace, showing my new design in a folded configuration;

FIG. 2 is a front elevation view thereof;

FIG. 3 is a rear elevation view thereof;

FIG. 4 is a top plan view thereof;

FIG. 5 is a bottom plan view thereof;

FIG. 6 is a right-side elevation view thereof;

FIG. 7 is a left-side elevation view thereof;

FIG. 8 is a front elevation view of the knee brace of FIG. 1, shown in an unfolded configuration for clarity of disclosure;

FIG. 9 is a rear elevation view thereof;

FIG. 10 is a right-side perspective view of the knee brace of FIG. 1, shown in condition of use for clarity of disclosure; and,

FIG. 11 is a left-side elevation view thereof.

The equal-length broken lines in the drawings depict environmental structure and form no part of the claimed design.

1 Claim, 11 Drawing Sheets
